UNITED STATES PATENT OFFICE.

IRVING J. ATKINS, OF DALLAS, TEXAS.

CLOTHES-PIN.

1,293,661.

Specification of Letters Patent. Patented Feb. 11, 1919.

Application filed July 27, 1918. Serial No. 247,006.

To all whom it may concern:

Be it known that I, IRVING J. ATKINS, a citizen of the United States, residing at Dallas, in the county of Dallas and State of Texas, have invented certain new and useful Improvements in Clothes-Pins, of which the following is a specification, reference being had to the accompanying drawings.

This invention relates to clothes pins, and particularly to spring clothes pins.

The general object of the invention is to form a metallic clothes pin of a single length of wire so bent as to provide spring actuated jaws, and a shank having an eye at its upper end whereby the pins may be readily assembled upon a carrying ring.

A further object is to so form the clothes pin that it may be readily and cheaply made.

Other objects will appear in the course of the following description.

My invention is illustrated in the accompanying drawings, wherein:

Figure 1 is a front elevation of a clothes pin constructed in accordance with my invention; and

Fig. 2 is a side elevation thereof.

Referring to these drawings, it will be seen that my improved clothes pin comprises a length of wire 10, which initially is bent at its middle so as to provide two legs or strands. The two strands are then again bent at 11 around a pin or other form and then the four strands thus formed are twisted together, as at 12, to provide a relatively rigid shank below the eye. The bight of the wire below this rigid twisted shank is formed into an elongated oval to provide a jaw 13. The lower end of this jaw 13 is outwardly deflected. The middle portion of this jaw is also slightly deflected as at 14. The opposing jaw, consists of the two strands of wire 10 which are disposed parallel to each other and between the two strands of the wire forming the loop 13 and the middle portion of this jaw is outwardly deflected as at 15 while the lower end of this jaw is outwardly deflected as at 16.

It will be seen that a clothes pin constructed as above described may be very cheaply made, that because of the twisting of the four strands of wire at the point 12, the shank of the pin is made relatively rigid and strong so that the pin will withstand hard usage and not be bent out of shape. The eye 11 permits the clothes pins to be strung upon the large open loop of wire so that the clothes pins may be very easily handled. Inasmuch as the pin is made of wire which is more or less resilient, the jaws will have their resilient clamping action when engaged over the clothes and on a line.

I claim:

1. A clothes pin formed from a single length of wire, the wire being bent at its middle to provide two legs, the legs being then bent upon themselves to form two opposing jaws, that portion of the bent wire opposite the jaws being formed to provide an eye and the several strands of wire between the eye and the jaws being twisted upon each other to provide a shank.

2. A clothes pin formed from a single length of wire the length of wire being bent at its middle to provide longitudinally extending legs, said legs being bent at their middle to provide four parallel strands of wire, the bight formed by the first named bend constituting a loop-shaped jaw and the ends of the strands opposite the bight forming an opposing jaw less in width than the width of the loop, that portion of the wire at the second named bend being formed to provide an eye and the strands of wire between said eye and the jaws being twisted in one direction to provide a shank, the jaws being deflected away from each other at the middle of the jaws and at the ends of the jaws.

In testimony whereof I hereunto affix my signature in the presence of two witnesses.

IRVING J. ATKINS.

Witnesses:

H. W. McMILLAN,
J. W. JERNIGAN.
